UNITED STATES PATENT OFFICE.

MICHAEL B. BULGER, OF BEAVER DAM, WISCONSIN, ASSIGNOR TO MIDDLE WEST MFG. CO., OF BEAVER DAM, WISCONSIN.

SNOW SHOVEL.

Application filed October 12, 1922. Serial No. 594,107.

To all whom it may concern:

Be it known that I, MICHAEL B. BULGER, a citizen of the United States, residing at Beaver Dam, in the county of Dodge and 5 State of Wisconsin, have invented a new and useful Snow Shovel, of which the following is a specification.

This invention aims to provide a snow shovel of simple construction which will 10 withstand the hard use to which devices of that sort commonly are subjected. Specifically, the invention aims to provide novel means for assembling the handle with the body of the shovel, and for reinforcing the 15 body.

It is within the province of the disclosure to improve generally and to enhance the utility of devices of that type to which the invention appertains.

20 With the above and other objects in view, which will appear as the description proceeds, the invention resides in the combination and arrangement of parts and in the details of construction hereinafter described 25 and claimed, it being understood that, within the scope of what is claimed, changes in the precise embodiment of the invention shown can be made without departing from the spirit of the invention.

30 In the accompanying drawings:—

Figure 1 shows in rear elevation, a shovel constructed in accordance with the invention; Figure 2 is a side elevation; Figure 3 is a detail enlarged from Figure 1; Figure 35 4 is a fragmental section.

In carrying out the invention, there is 40 provided a body 1 of any desired shape and preferably made of metal, the body being supplied at its upper end with an overhanging flange 17 which forms a stop, preventing the snow from sliding off the body. The body 1 is provided along its upper edge and along its sides with a marginal stiffening bead 2. A blade 3 is overlapped on the forward surface of the body 1 at the lower end thereof and is connected thereto by securing elements 4, the blade preferably being made of tempered steel, so as to withstand wear.

The device comprises a reinforcing frame, 50 including diverging braces 6, united at their upper ends by a connecting portion 61 received in a notch 50 formed in the forward edge of a reinforcing member 5, hereinafter mentioned. The frame above alluded to is

applied to the rear surface of the body 1 55 and is held thereon, at its lower ends, by certain of the securing elements 4, which pass through the lower ends of the diverging brace members 6 of the frame. A socket 8 abuts against the rear surface of the body 1 of the shovel and has an upstanding lip 9. The aforesaid reinforcing member 5 is formed integrally with the lower end of the socket 8 and extends downwardly along the body 1 of the shovel, the lower end of the 60 reinforcing member being connected to the body by one of the securing elements 4. Depending flanges 29 are formed integrally with the socket 8 and with the reinforcing member 5 and are located on opposite sides 65 of the reinforcing member. The flanges 29 are overlapped on the connecting portion 61 which joins the braces 6. Securing members 7 pass through the flanges 29, through the connecting portion 61 of the braces 6, 70 and through the body 1. The forward wall 51 of the socket 8 is upwardly extended and carries a transverse annular keeper 10. The numeral 11 marks a handle, provided at its upper end with the grip 12. The handle 11 passes downwardly through the keeper 10 and has a tapered end 14 received in the socket 8. A securing element 16 passes 75 through the rear wall of the socket 8 and enters the tapered end 14 of the handle 11. 80 A securing device 15, such as a rivet, is engaged with the keeper 10, with the forward wall 51 of the socket, with the body 1, and with the handle 11.

The resulting product is a snow shovel 90 well adapted to withstand hard use and so constructed that the snow will slip readily therefrom. Should any of such parts as the member 5 and the socket 8, or the frame including the brace member 6 become broken, 95 they may be replaced readily, and it will be unnecessary to throw away the entire shovel.

What is claimed is:—

1. In a device of the class described, a body, an integral reinforcing frame including diverging braces united by a connecting portion, a socket bearing against the body and provided at its lower end with a reinforcing member bearing against the body and located between the braces, the reinforcing member being thicker than the connecting portion of the frame and being provided 100 in its forward edge with a notch through 105

which the connecting portion of the frame passes, and means for securing the frame and the reinforcing member to the body.

2. A device of the class described, constructed as set forth in claim 1, and further characterized by the fact that said means embodies flanges on the socket on opposite sides of the reinforcing member, and overlapped on the connecting portion of the

frame; and securing elements uniting the 10 flanges, the connecting portion and the body.

In testimony that I claim the foregoing as my own, I have hereto affixed my signature in the presence of two witnesses.

MICHAEL B. BULGER.
